UNITED STATES PATENT OFFICE.

FREDERICK D. SCHNEIDER, OF NEW BRUNSWICK, NEW JERSEY, ASSIGNOR TO THE LONG-LANDRETH SCHNEIDER CO., OF NEW BRUNSWICK, NEW JERSEY.

HEATER CONSTRUCTION.

1,246,332.

Specification of Letters Patent.

Patented Nov. 13, 1917.

Application filed December 9, 1914. Serial No. 876,272.

To all whom it may concern:

Be it known that I, FREDERICK D. SCHNEIDER, a citizen of the United States, residing at New Brunswick, in the State 5 of New Jersey and county of Middlesex, have invented a new and useful Improvement in Heater Constructions, of which the following is a specification, the principle of the invention being herein explained and 10 the best mode in which I have contemplated applying that principle, so as to distinguish it from other inventions.

This invention has general reference to heater constructions and more particularly 15 to the features incident to its structural arrangement. Heretofore two types of heater have been employed for the purpose of heating the water supply required for domestic usage. One consisted of a heater of small 20 capacity which heated the water contained within a comparatively large storage tank. While this type gave service it was wasteful and extravagant due to the loss by heat radiation when keeping a large tank hot. The other 25 utilized a heating conduit of capacity meant to be large enough to sufficiently heat the flow from a faucet under normal pressure, and the burners of which were automatically lighted from a pilot flame when the gas valve 30 was opened by the water pressure. At times this type was too large and frequently too small when an inordinate supply was required. Conditions under one extreme made it wasteful and under the other extreme 35 temporarily insufficient. My new type of water heater involves a comparatively small storage supply with a large capacity heating conduit.

My structure is designed to effect advantages in the way of compactness, accessibility 40 to the interior and general efficiency.

The object of my invention has been to confine within a suitable casing both a storage tank and a water conduit. The latter 45 is readily separable into flat sections, which, partly by reason of their configuration, are quickly detached and the withdrawal of which thereafter for the purposes of cleansing, repair or replacement is greatly facilitated.

The inventive conception is associated with means which are hereinafter explained and variously combined in the claims. While the annexed drawings and particular 55 description thereof, set forth the preferred

form embodying my invention, it should be understood that the means only exemplifies one of many diversified mechanical forms with which the principle of my invention may be properly applied. 60

Figure I is a side elevation of an exemplifying heater construction embodying my invention.

Fig. II is an end view of Fig. I showing certain parts broken away. 65

Fig. III is a view corresponding to Fig. I with the front of the casing removed in section to disclose the interior.

Fig. IV is a section on line IV—IV of Fig. III looking to the left as directed by 70 the arrows.

Fig. V is an elevation of a portion of the water conduit.

Inasmuch as it is with only two features each involving interrelated functions, that 75 this invention has to do; mention will be very brief of all parts the construction or arrangement of which has no direct bearing upon the efficacy of this invention. A casing designated entirely with the reference 80 character A comprises suitable legs a¹, a perforate base a², supporting near one end one or more burner seats a³ one of which is well shown in Fig. III. The front wall a⁴ of the casing is provided in its lower part with a 85 door a⁵ whereas the rear wall a⁶ of the casing is provided with an opening near its top which is in connection with a stack a⁷. It will be noticed that the casing involves a double set of walls the inner one of which may 90 be cast iron and the outer any suitable insulating material. One of the ends, namely the one at the left as appears in Fig. III is provided near its bottom with a number of openings a⁸, in this instance four, to correspond with the number of burners employed 95 in this particular exemplification. The openings a⁸ are disposed substantially on a level with the tops of the burner supports a³. Some distance higher up the end a⁸ of the 100 casing is provided with additional openings a¹⁰ which reference character should be assumed as applied to an opening in both walls as a unit. Actually there are six of these openings and their purpose will hereinafter appear. The upper extremity of the end a⁸ is fashioned with an approximately semicircular recess a¹¹ of maximum dimensions. The opposite end a¹² of the 105 casing is provided midway with a large 110

opening a^{13} corresponding in height with the height of the door a^5 though positioned somewhat higher up. This opening a^{13} should similarly be understood to extend 5 through both walls of the end a^{12} of the casing, as is again apparent in Fig. III. The upper extremity of the end a^{12} is provided with a recess a^{14} similar to the recess a^{11} . A removable panel a^{15} is adapted to close 10 the opening a^{13} when affixed as by screws a^{16} . The upper and lower edges of the panel a^{15} are provided with six equally spaced grooves, those above being designated as a^{17} and the lower ones as a^{18} . Each super- 15 posed pair of grooves a^{17} and a^{18} is disposed in the same endwise plane as one of the openings a^{10} . These grooves are best seen in Fig. II, such parts as are broken away having been so shown for the very purpose of 20 disclosing these grooves.

Seated and suitably packed within the recesses a^{11} and a^{14} so as to effectually close the upper end of the casing A and be in turn partially enveloped thereby is an elongated 25 storage tank B of smaller capacity than has heretofore been generally employed. One end of the tank, namely the left end is provided with a conduit inlet b' . Above, a pipe b^3 will be presumed as leading to the faucet. 30 The outlet b^2 communicates by means of a flange connection b^4 with a manifold b^5 provided below with an opening b^6 intended for the insertion of the sensitive element of a thermostat. While this manifold has six 35 outlet openings corresponding with and spaced as the grooves a^{17} connections with only one will be described. Connected with the outlet of the manifold b^5 is the male part b^7 of the common type of union. The 40 female part b^8 of this union is supported upon the upper inlet extremity b^9 of a zig-zag interiorly positioned portion of the water conduit. This conduit is clearly shown in both Figs. III and V to embody the well 45 known principle of both a downward and an upward flow. According to my invention however, the interiorly disposed portion or portions of the conduit with its alternately inclined interjacent sections are 50 substantially flat in its entirety so as to be capable of lying within a vertical plane as is well shown in Fig. IV. Such alternate inclination involves above straight interjacent sections b^{10} connected by return bends 55 b^{11} through which the water travels downwardly, next a directly downwardly extending portion b^{12} leading into a T b^{13} to which a drain cock b^{14} is connected. This cock projects outwardly through the groove 60 a^{18} as is shown in Figs. II and III. Thereafter the travel of the water is upwardly through straight alternately inclined sections b^{15} and return bends b^{16} . The outlet extremity b^{17} passes through the opening a^{10} 65 and carries the female part a^{18} of another

union. The male part b^{19} of such union is likewise connected with one of the inlets of a manifold b^{20} which is in turn connected at b^{21} with a pipe b^{22} communicating with the inlet b' . 70

It should now be manifest that owing in part to the configuration of so much of the water conduit as is disposed within the confines of the casing, and in part to the provision of the removable panel a^{15} in one of the interior conduit units may be withdrawn through the opening a^{13} after disconnection from the manifolds b^5 and b^{20} . Thus a facility is occasioned by removing any section of the conduit which has developed a flaw or for any other reason, and this may furthermore be accomplished independently or without disturbing in any wise the connection of any other conduit section. 75 80 85

A plurality and in this instance four 90 burners C, having inlet ends c' extending through the openings a^9 and opposite extremities c^2 are suitably mounted upon the supports a^3 . The burners C each carry a plurality of removable stools c^3 . Secured 95 to the inlet ends c' outwardly of the end a^8 of the casing, is a mixing valve c^4 connected by a pipe length c^5 with a gas manifold c^6 leading through the agency of a bent pipe connection c^7 to a valve c^8 in connection with the source of fuel supply. The operation of the valve c^8 is controlled by means of the type of thermostat c^9 earlier referred to and which comprises a sensitive tube c^{10} adapted by means of a flexible connection c^{11} to actuate the valve stem c^{12} . 100

I claim:—

1. A heater construction comprising a casing, a storage tank thereon, heating means in communication therewith, a zig-zag water conduit above said heating means and connected with said tank, opposite extremities of said conduit being detachably connected, and a panel disposed endwise of said conduit and adapted to permit the withdrawal of the conduit therethrough, said panel being fashioned with grooves for the reception of said conduit extremities whereby to facilitate fitting and holding of the panel in place. 110 115

2. A heater construction comprising a casing, a tank above, an elongated burner construction below, a plurality of laterally adjacent zigzag water conduits having longitudinally extending interjacent portions and communicating with said tank, inlet and outlet manifolds communicating with inlet and outlet ends of said conduits respectively and with said tank, said inlet and outlet ends being detachably connected to said manifolds, and a removable panel in one end of said casing through which individual of said conduits may be withdrawn independently of each other, said panel being fashioned with grooves in the 120 125 130

top and bottom edges thereof corresponding in number to said individual conduits, said inlet and outlet ends being seated in said grooves whereby to determine the proper 5 position of and hold said panel in place.

3. In an apparatus for heating and causing the circulation of a fluid, a conduit system which includes a zigzag passage comprising elongated interjacent portions and 10 having a continuously downward direction from its inlet to its discharge end, a second zigzag passage comprising elongated interjacent portions located below the first and having a continuously upward direction 15 from its inlet toward its outlet end, and a duct which connects the lower discharge end of the first mentioned passage and the lower intake end of the second mentioned passage, heating means located below said 20 passages, an elongated hot water storage

tank from which service water is adapted to be drawn, said tank being located above and connected to said passages, an inclosing casing which embraces said passages, tank and heating means whereby heat from 25 the latter is directly applied to the tank and a removable panel at one end of said casing, said panel being provided with a groove in each of its top and bottom edges for the reception of sections of said passage, 30 the engagement being such that said zigzag passage may be withdrawn endwise from beneath said tank without disturbing any connections of the latter.

Signed by me, this 2nd day of December, 35
1914.

FREDERICK D. SCHNEIDER.
